UNITED STATES PATENT OFFICE

PAUL M. KUEHN, OF BALTIMORE, MARYLAND, ASSIGNOR TO THE BARTLETT HAYWARD COMPANY, OF BALTIMORE, MARYLAND, A CORPORATION OF MARYLAND

GAS HOLDER

Application filed April 14, 1928. Serial No. 270,036.

This invention pertains to gas holders and relates more particularly to means employed for securing an admixture of the gas within the holder, this with a view of maintaining as near as possible a uniform or means condition of the gas which is withdrawn therefrom.

While the invention is applicable to the handling of blast furnace gas, particularly where such gas is to be employed for firing coke ovens, the invention in its broader aspect is of general applicability.

Stated in a generic way the invention may be said to comprise means to insure, by the utilization of the pressure of the incoming gas stream which is forced through a high speed nozzle, an admixing of the gas content of the holder whereby stratification of the gas due to varying specific gravities and other conditions is prevented.

I am aware that broadly considered it is not new to inject a stream of gas into the body of gas within a holder for the purpose of securing an admixture within the gas body, but the present invention differs therefrom in that the entire body of incoming gas is forced through a nozzle and is thereby caused to intermix with the entire body of gas within the holder, thereby insuring a mean condition of the gas which is withdrawn from the holder.

Furthermore, by locating the high speed nozzle to one side of the center of the holder, a highly effective mixing action is obtained. Again, the high speed nozzle, as hereinafter set forth, is of the aspirator type and the shell of the aspirator is provided with leader pipes that draw gas from remote points within the holder and mix it in the outlet of the aspirator itself with the inflow from the main. Any or all of these features are effective in carrying out the practical purposes of the invention in its several aspects above mentioned or hereinafter described or claimed.

The invention will be best understood upon reference to the annexed drawings wherein:

Figure 1 is a vertical sectional elevation of a holder of the "waterless type" illustrating the inlet line or trunk for the gas, taken on the line I—I of Figure 2,

Figure 2 a horizontal section on the line II—II of Figure 1,

Figure 3 a detail vertical sectional view of the injector nozzle employed through which the gas is introduced into the holder,

Figure 4 a like view taken on the line IV—IV of Figure 3, and

Figure 5 a detail view illustrative of a simple nozzle connected to the inlet trunk or line, the nozzle being shown in vertical section and the pipe leading thereto in elevation.

Referring first to Figures 1 to 4, 1 denotes the shell of the gas holder having mounted therein a movable piston or diaphragm 2, which latter carries at its periphery suitable sealing means to prevent the escape of gas. Such construction is well known in the art, hence no detailed description is herein given.

The piston, of course, moves up and down under varying gas pressure.

As above indicated, it is desirable to secure within the holder a thorough admixture of the entire body of gas introduced into the holder and to this end I provide, as an extension of the inlet main 3, a trunk or inlet pipe 4, which latter is flattened or non-circular in cross section in order to allow the piston to move downwardly as the gas is withdrawn from the holder. The trunk or member 4 will preferably be given the same cross sectional area as the main 3 so that the full volume of gas which is forced in through the main will pass through the trunk 4 to a nozzle 5 connected to the outer end thereof and pointing in an upward direction. This nozzle is preferably of the injector type; that is to say it is surrounded by a shell or casing 6 which terminates above the upper end of the nozzle 5 and is provided with a series of lateral openings from which extend intake pipes 7. Said pipes radiate from the outer member 6 and as a consequence cover considerable area within the bottom of the holder. In other words, the inlets of the various pipes draw the gas from remote points and thus tend to set up a complete circulation and prevent the formation of pockets in

100

which the gas would otherwise become stagnant.

In action, gas flowing through the main 3, 4 under pressure passes upwardly from the nozzle 5 to one side of the center of the holder, and, owing to its velocity, induces an in-drawing of the gas through the pipes 7 and the projection of such gas, along with the gas flowing from the nozzle 5, upwardly into the tank whereby the body of the gas held within the tank below the movable closure or piston 2 will be thoroughly agitated and intermingled. This is of advantage where the gas is being drawn from various furnace units, as for instance, blast furnaces, wherein the output of gas as to quality and physical characteristics will vary.

Preferably the gas off-take from the holder will be located remote from the nozzle and 20 in Figure 2 there is shown an off-take pipe or main 8 which extends inwardly of the body 1 and provided with a plurality of openings as 9 and 10.

In order to permit the piston 2 to come 25 down to the bottom of the holder the piston will preferably be formed with a hood-piece or cap 11 overlying an opening 12 formed in the piston and through which the nozzle 6 will extend when the piston is lowered.

30 While it is preferred to employ a nozzle of the injector type, still a simple high speed nozzle may be found all sufficient and in Figure 5, I have illustrated such a nozzle, which is designated 13.

35 While, as just noted, the construction first described is preferred in that it draws gas from portions of the lower part of the holder remote from the nozzle and recirculates the same, still both forms are effective.

40 It is to be noted, moreover, that under both constructions preferably substantially the entire volume of the incoming gas from the main passes through the high speed nozzle, a point of manifest advantage. This is particularly so over such constructions wherein it is sought to set up agitation within the holder by employing a special pump designed to handle a limited portion only of the incoming gas and to force the same through 45 a nozzle located within the holder.

What is claimed is:

1. In combination with a gas holder; a gas inlet main extending into the holder; an injector nozzle secured to the inner end of the 55 main; a plurality of laterally extending open ended gas circulating pipes connected to the nozzle within the holder; and a gas discharge outlet for the holder.

2. In a gas holder, the combination of a 60 piston-like closure mounted therein, said closure having an opening therein; a hood-like member overlying said opening; a gas inlet main extending into the holder at the bottom thereof; an injector nozzle connected to the inner end of said main, said noz-

zle standing in vertical alignment with the hood carried by the closure; a plurality of laterally extending, open ended gas circulating pipes connected to the nozzle within the holder; and a gas discharge outlet for the 70

3. In combination with a gas holder; a gas inlet main extending into the holder; an injector nozzle secured to the inner end of the main within the holder; at least one open ended gas circulating pipe connected into the shell of the nozzle and extending laterally therefrom to a substantially remote point within the holder; and a gas discharge outlet for the holder. 75

4. In combination with a gas holder: a gas inlet main extending into the holder and terminating in an aspirator nozzle located to one side of the center of the bottom portion of the holder; and open-ended gas circulating pipes connected into the shell of the aspirator and leading from points within the lower portion of the holder that are substantially remote from said nozzle; whereby substantially the whole inflow 80 from the main is forced into admixture with gas drawn from diversely disposed regions of the holder.

In testimony whereof I have signed my name to this specification.

PAUL M. KUEHN.
